UNITED STATES PATENT OFFICE.

EDWARD VROOM, OF OSSINING, NEW YORK, ASSIGNOR TO WESTERN ELECTRIC COMPANY, INCORPORATED, OF NEW YORK, N. Y., A CORPORATION OF NEW YORK.

MEANS FOR ENERGIZING ELECTRON TUBES.

Application filed August 20, 1923. Serial No. 658,243.

This invention relates to circuits for energizing repeaters, and aims to improve such circuits and reduce the amount of apparatus required therein.

- 5 In the specific form of the invention shown in the accompanying drawings a single battery supply unit is so arranged that it may conveniently be used to supply the plate, filament and grid voltages for electron tube 10 amplifier groups, one group at a time, where the groups employ different numbers of electron tubes or space current paths. By way of example, one of the groups of amplifiers shown may be regarded as the amplifier of 15 22 type repeater employing two tubes, another group shown may be regarded as the amplifiers of a 21-type phantom repeater group employing three tubes, and a third group shown may be regarded as the amplifiers 20 of two 22-type repeaters employing two tubes each. The significance of the expressions, 21 type repeater and 22 type repeater, is explained in the article entitled, "Telephone repeaters," by Messrs. Gherardi and 25 Jewett, Proceedings of the American Institute of Electrical Engineers, 1919, page 1255; a 21 type phantom repeater group is disclosed in Blackwell Patent No. 1,474,430, November 20, 1923, and in Mathes Patent 30 1,495,422, May 27, 1924; and 22 and 21 types of repeaters are shown in Figs. 1 and 3, respectively, of Mathes 1,472,610, October 30, 1923, and in Figs. 4 and 3, respectively, of Colpitts 1,128,292, February 16, 1925. Moreover, a common filament circuit battery supplies filament heating current for all of the tubes of which ever one of these three groups is connected to the battery supply circuit, and a common plate current battery supplies 40 current for all of the plate circuits of the group of tubes. Further, in each of the amplifier groups, the space current circuits of the tubes are connected in parallel, and the filaments of the tubes are connected in series, and to compensate for the resulting differences in the potential drop between the plate and filament in the different tubes of the group, resistances of different values are incorporated in the space current circuits, these 45 resistances being preferably embodied in means for indicating the absence of space current in the tubes, or for indicating absence of filament current since flow of space current is, of course, dependent upon flow of 50 filament current.
- Fig. 1 of the drawings is a diagram showing a battery supply circuit made in accordance with the invention connected to a repeater group, for instance two 22-type repeaters comprising four filaments connected 60 in series; Fig. 2 is a diagram indicating circuit connections employed when the battery supply circuit of Fig. 1 is used to energize a repeater group, for instance a 21-type phantom repeater group, employing but 65 three filaments in series; and Fig. 3 is a diagram showing the circuit connections employed when the battery supply circuit of Fig. 1 is used to energize a group of amplifiers, for instance a 22-type repeater, employing but two filaments in series. 70
- In Fig. 1 a filament current battery 5 has its positive pole connected to a grounded bus bar 6 and its negative pole connected to a bus bar 7. A plate current battery 8 has its 75 negative pole connected to bus bar 6 and its positive pole connected to bus bar 9. Four electron tubes 10, 11, 12 and 13 have their filaments fed in series from battery 5. It may be considered, by way of example, that 80 tubes 10 and 11 are amplifiers of one 22-type repeater and tubes 12 and 13 are amplifiers of another 22-type repeater. Space current is supplied to tubes 10 to 13 in parallel from battery 8. Grid potentials for the tubes 10 to 85 13 are supplied by batteries 14 to 17 respectively. The tubes 10 to 13 may be mounted on, for instance, a repeater panel or panels (not shown) adapted for relay rack mounting, after the general fashion in 90 which the repeater bulbs are mounted on the relay rack panels in D. F. Whiting Patent No. 1,442,456, January 16, 1923, and in Figs. 5 to 7 of the article on "Telephone equipment for long cable circuits" by C. S. Demarest, Bell System Technical Journal, July 95 1923. For example, tubes 10 and 11 may be mounted on repeater panel 39^a, and tubes 12 and 13 on a similar repeater panel 39^b. Leads from the electrodes of the tubes 10 to 100 13 connect those electrodes as shown to terminals 40 to 53, each of which may be on the panel upon which is mounted the tube containing the electrode to which that terminal is connected. Thus, the terminals 40, 46, 47, and 53 may be regarded as grid terminals on the repeater panels; the terminals 41, 45, 48 and 52 as plate terminals on the repeater panels; and the terminals 42, 43, 44, 49, 50 and 51 as filament terminals on the 105 110

repeater panels. Corresponding to the repeater panel grid terminals 40, 46, 47 and 53 are battery supply panel grid terminals 20, 26, 27 and 35 respectively, connected thereto, and mounted on a battery supply panel 100 which may also be adapted for relay rack mounting. Corresponding to the repeater panel plate terminals 41, 45, 48 and 52 are battery supply panel plate terminals 10 21, 25, 28, and 34, respectively connected thereto and mounted on the panel 100; and also on the battery supply panel 100, are battery supply panel filament circuit terminals 22, 23, 24, 29, 30, 31, 32 and 33. As is 15 shown in the drawing, the battery supply panel filament circuit terminals 22, 23, 24, 30 and 31 and connected to corresponding repeater panel filament terminals 42, 43, 44, 50 and 51, respectively, and the terminal 24 20 is also connected to the repeater panel filament terminal 49. The battery supply panel filament circuit terminals 29, 32 and 33 are idle in Fig. 1, being provided for facilitating the insertion in the filament heating circuit 25 to be connected to the battery supply panel, of resistances 60 and 61 in place of the filaments of tubes 12 and 13 when the filament heating circuit is to contain less than four filaments in series, as will be explained hereinafter in connection with Figs. 2 and 3.

Terminals designated 36, 37 and 38 in the drawing are mounted on the battery supply panel 100, and are strapped together in Fig. 35 1, these terminals being provided for facilitating the proper connection of a relay 62, the function of which will be pointed out hereinafter, to the plate circuits to be connected to the battery supply panel 100 when 40 the number of space current paths fed from the panel is to be less than four, as will be explained hereinafter in connection with Figs. 2 and 3.

In Fig. 1, relays 65, 66, 67 and 68 have 45 their windings connected in series in the plate circuits of tubes 10, 11, 12 and 13 respectively, and hold their respective contacts open when the values of the space currents passing through their windings is sufficiently high for proper operation of the tubes. If any of these space currents falls below a predetermined value, the corresponding relay will release its armature, thereby causing the energization of a signal lamp 69 and the relay 62, both of which 50 are in a local circuit of a battery 70, the lamp, the winding of relay 62, and battery all three being in series with a circuit comprising the four contacts of relays 65, 66, 67, 55 and 68 in parallel. Thus the lamp 69 serves as a low space current alarm for the tubes connected to the battery supply panel 100. The relay 62, when energized, closes a local 60 circuit for a bell or other signal device 71, 65 which therefore also serves as a low space

current alarm for the tubes connected to the panel 100. By means of leads such as those indicated at 72 and 73 as connected to a bus bar 74 to which the coil of relay 62 is shown connected, that coil may also be connected 70 to other battery supply panels than the panel 100, after the fashion in which it is connected to panel 100. Thus, the relay 62 and signal 71 may serve as a low space current alarm for tubes connected to a plurality 75 of battery supply panels, the signal 69, or the corresponding signal for each panel, indicating the panel to which any space current circuit causing the operation of signal 71 is connected. Preferably the signal 71 is 80 an audible signal and the signal 69 a visual signal.

The filament circuit for the tubes connected to the battery supply panel 100 in Fig. 1 extends from bus bar 6 through a 85 terminal 6' on the panel 100, the upper contacts of a key 75, terminals 31 and 51, the filament of tube 13, the filament of tube 12, terminals 49, 24, and 44, and the filament of tube 11, the filament of tube 10, 90 terminals 42 and 22, a terminal 7' on the panel 100, a filament current adjusting resistance 76, and a choke coil 77 for reducing fluctuations of filament current due to internal changes in battery 5 or the like, to bus 95 bar 7.

The plate circuit for tube 10 extends from bus bar 9 through a terminal 9' on the panel 100, the winding of relay 65, terminals 21 and 41, the plate of tube 10, the 100 space current path in tube 10, and the filament circuit, to bus bar 6.

The plate circuit for tube 11 extends from bus bar 9 through the terminals 9', coil of relay 66, terminals 25 and 45, the plate of 105 tube 11, the space current path in tube 11, and the filament circuit, to bus bar 6.

The plate circuit of tube 12 extends from bus bar 9 to the terminals 9' on the panel 100, and through the coil of relay 67, terminals 28 and 48, the plate of tube 12, the space current path in the tube, and the filament circuit to bus bar 6.

The plate circuit of tube 13 extends from bus bar 9 and terminal 9' through the coil 115 of relay 68, terminals 34 and 52, the plate of tube 12, the space current path in the tube, and the filament circuit, to bus bar 6.

The grid circuit for tube 10 extends from the terminal 42 which connects with the negative end of the filament of that tube, to terminal 22, and through grid battery 14, terminals 20 and 40, to the grid of the tube.

The grid circuit of tube 11 extends from terminal 43, which is at a point on the filament heating circuit located between the negative end of the filament of tube 11 and the positive end of the filament of tube 10, through terminal 23, grid battery 15, and terminals 26 and 46, to the grid of tube 11.

The grid circuit of tube 12 extends from terminal 49 which connects with the negative end of the filament of that tube, to terminal 24 and through grid battery 16, and 5 terminals 27 and 47, to the grid of the tube.

The grid circuit of tube 13 extends from terminal 50, which is at a point between the negative end of the filament of tube 13 and the positive end of the filament of tube 12, 10 through terminals 30, grid battery 17, and terminals 35 and 53 to the grid of tube 13.

The key 75 has its lower contacts in series with battery 70, so that when the key is operated to open the filament circuit of 15 tubes 10, 11, 12 and 13 at its upper contacts, it will also open the circuit of battery 70, and thereby prevent the operation of the signal devices 69 and 71.

By means of leads such as those indicated 20 at 78, bus bars 6, 7 and 9 may supply energy from batteries 5 and 8 to battery supply panels (not shown) similar to the battery supply panel 100.

The repeater panel 39^a is shown broken 25 away at the left-hand side of tubes 10 and 11. Similarly, the repeater panel 39^b is shown as broken away at the left-hand side of tubes 12 and 13. For the sake of simplicity, the apparatus ordinarily associated 30 with the repeating tubes and their battery supply connections and mounted on the repeater panels, has been omitted from the drawing. Only such portions of the alternating current circuits as are included in the 35 direct current and potential circuits, are shown herein.

The batteries 14 to 17, the resistances 60 and 61, the relay 65 to 68, the key 75 and the lamp 69 are preferably mounted on the 40 panel 100, as indicated in the drawing.

As explained in A. F. Rose Patent 1,436,683, November 28, 1922, battery supply circuits for repeaters, where tubes have their space current circuits in parallel and their 45 filaments in series, the voltage drops in the filaments tend to cause the plate-to-filament voltage to be different for the different tubes, and to compensate for this difference, resistances of different values may be inserted in the space current circuits of the 50 different tubes. In accordance with the present invention, the compensating resistances are embodied in the windings of the relays 65 to 68, thus reducing the amount 55 of apparatus required and reducing the mounting space required on the battery supply panel. As indicated in the drawing, relay 67 has a resistance greater than that of relay 68; relay 66 has a still greater 60 resistance; and relay 65 a resistance greater than that of relay 66. The principles underlying the proper proportioning of the resistances are fully set forth in the Rose patent mentioned above.

65 The windings of relays 65 to 68 serve as

choke coils for preventing alternating current output from any of the tubes from passing through the common plate battery 8 and thereby causing cross-talk.

Fig. 2 shows the circuit connection to terminals 20 to 38 when the panel 100 is used to supply the plate, filament, and grid circuits of three tubes 10', 11' and 12' having their filaments connected in series. The tubes may be, for example, the tubes of a 21-type phantom repeater group, and the tubes may be mounted on a repeater panel 39' adapted for relay rack mounting. The electrodes of the tubes 10' to 12' are connected to terminals 240 to 250 mounted on the 80 panel 39', just as the corresponding electrodes of the respectively corresponding tubes 10 to 12 are connected to the respectively corresponding terminals 40 to 50 in Fig. 1. The panel 39' is shown broken away 85 just to the left of the tubes 10' to 12', and the panel 100 in Fig. 2 is shown broken away just to the right of the terminals 20 to 38. The circuit connections to terminals 20 to 38 in Fig. 2 are shown broken away along the line L, L, which is the same as line L, L in Fig. 1, and these circuit connections to the right of line L, L are to be understood as being the same for Fig. 2 as for Fig. 1.

Comparing the circuit connections to terminals 240 to 250 and 20 to 38 of Fig. 2 with the circuit connections to terminals 40 to 50 and 20 to 38 of Fig. 1, it will be seen that all of the terminals 240 to 250, except terminal 250, that is, all of the terminals 100 240 to 249, are connected to terminals 20 to 28 in Fig. 2 exactly as the respectively corresponding terminals 40 to 49 are connected to terminals 20 to 28 in Fig. 1. Terminal 30, which in Fig. 1 was strapped to terminal 50 in order to connect the grid circuit of tube 13 to the filament of that tube, is idle in Fig. 2, since the circuit of Fig. 2 has no tube corresponding to the tube 13 of Fig. 1. In Fig. 2 the resistance 61, which has approximately the value of the resistance of the filament of tube 13 of Fig. 1, is substituted for that filament in the filament circuit, so that the plate-to-filament voltages in the tubes 10', 11' and 12' will be the same as 110 were the plate-to-filament voltages in the tubes 10, 11 and 12, respectively, and the filament heating current will be the same as in Fig. 1. To accomplish this insertion of 115 resistance 61 in the filament circuit, terminal 31, which in Fig. 1 was strapped to terminal 51 connected to the positive end of the filament of tube 13, is strapped to terminal 32, at the upper end of resistance 61, and terminal 33, which connects with the lower end of resistance 61 and was idle in Fig. 1, is strapped to terminal 250 which connects with the positive, or high voltage, end of the filament of tube 12'. Terminals 34 and 35, 120 which in Fig. 1 were strapped to the repeater 125 130

panel plate and grid terminals 52 and 53, respectively of tube 13, are idle in Fig. 2. Terminal 36, which connects with the contact of relay 68 and in Fig. 1 was strapped 5 to terminals 37 and 38 to connect the contact of relay 68 in parallel with the contacts of relays 65, 66 and 67, is idle in Fig. 2, so that the signals 69 and 71 will not be operated because of the closed condition of the 10 contact of relay 68.

Fig. 3 shows the circuit connections to terminals 20 to 38 when panel 100 is used to supply the plate, filament and grid circuits of two tubes 10" and 11" having their 15 filaments connected in series. The amplifier group may be, for example, that of a 22-type repeater, such as the repeater comprising the tubes 10 and 11 of Fig. 1, and the tubes 10" and 11" may be mounted on a repeater 20 panel 39^e shown broken away just to the left of tubes 10" and 11". The electrodes of the tubes are connected to terminals 340 to 346 mounted on the panel 39^e, just as the corresponding electrodes of the tubes 10 and 25 11 are connected to the respectively corresponding terminals 40 to 46 in Fig. 1. The panel 100 is shown broken away just to the right of terminals 20 to 38. The circuit connections to terminals 20 to 38 in Fig. 3 are 30 shown broken away along the line L, L, which is the same as the line L, L in Fig. 1 and these circuit connections to the right of line L, L are to be understood as being the same for Fig. 3 as for Fig. 1.

It will be seen that the interconnections 35 between terminals 340 to 346 and 20 to 26 in Fig. 3 are exactly the same as those between terminals 240 to 246 and 20 to 26 in Fig. 2. In Fig. 3, terminals 27 and 28, 40 which in Fig. 2 were strapped to terminals 247 and 248 connected with the grid and plate, respectively, of tube 12', are idle. In Fig. 3, the terminal 33, which connects with the lower end of resistance 61 and which 45 in Fig. 2 was strapped to terminal 250 that connected to the high voltage end of the filament of tube 12' is strapped to terminal 29, so that the resistance 60, which was idle in Fig. 2, is inserted in the filament heating 50 circuit in place of the filament of tube 12', in order to make the value of the filament heating current the same in Fig. 3 as in

Fig. 2, and in order to make the plate-to-filament drop in tubes 10", and 11" the same as that in tubes 10' and 11' respectively. Terminals 27 and 28, which in Fig. 2 were strapped to the repeater panel plate and grid terminals 247 and 248 respectively, of tube 12', are idle in Fig. 3. Terminal 37, which connects with the contact of relay 67 and in Fig. 2 was strapped to terminal 38 to connect the contact of relay 67 in parallel with the contacts of relays 65 and 66, is idle in Fig. 3, so that the signals 69 and 71 will not be operated because of the closed condition of the contact of relay 67. 55 60 65

The invention claimed is:

1. In a repeater system, two electron tube repeater elements each including a filament and an anode, a source of filament heating current, the filaments of said tubes being connected in series circuit with said source, a source of space current, parallel connections from said last named source to the filament and anode of said tubes, and means for indicating the condition of said tubes, said means comprising resistance in one of said parallel connections so proportioned as to compensate for the difference in potential drops across the plates and filaments of the different tubes due to the series connections of the filaments. 70 75 80

2. In a repeater system, two electron tube repeater elements each including a filament and an anode, a source of filament heating current, the filaments of said tubes being connected in series circuit with said source, a source of space current, parallel connections from said last named source to the filament and anode of said tubes, and means for indicating absence of space current in one of said tubes, said means comprising a relay having a winding in one of said parallel connections, said winding having a 90 95 resistance so proportioned as to compensate for the difference in potential drops across the plates and filaments of the different tubes due to the series connections of the filaments. 100

In witness whereof, I hereunto subscribe my name this 18th day of August A. D., 1923.

EDWARD VROOM.
